CLAIM

The ornamental design for a juvenile vehicle seat, as shown and described.

DESCRIPTION

FIG. 1 is a perspective view of a juvenile vehicle seat showing a first embodiment of my new design;

FIG. 2 is a left-side elevational view thereof, with the right-side elevational view being a mirror image thereof;

FIG. 3 is a front elevational view thereof;

FIG. 4 is a rear elevational view thereof;

FIG. 5 is a top plan view thereof;

FIG. 6 is a bottom view thereof;

FIG. 7 is a perspective view of a juvenile vehicle seat showing a second embodiment of my new design;

FIG. 8 is a left-side elevational view thereof, with the right-side elevational view being a mirror image thereof;

FIG. 9 is a front elevational view thereof;

FIG. 10 is a rear elevational view thereof;

FIG. 11 is a top plan view thereof; and,

FIG. 12 is a bottom view thereof.
